J. E. WRIGHT

CALCULATING DEVICE

Filed Oct. 31, 1925

UNITED STATES PATENT OFFICE.

JOHN E. WRIGHT, OF MAYFIELD, KENTUCKY.

CALCULATING DEVICE.

Application filed October 31, 1925. Serial No. 66,020.

This invention relates to a flexible band or web, adapted to be wound upon a cylinder, roller, spool or the like, and bearing integrations that are so arranged that readings may be taken therefrom with reference to the integrations borne by another member or members.

In a co-pending application, filed coincidentally herewith, Serial No. 66,021, I have described and claimed a calculator for use with which the improved form of integration table referred to herein is especially adapted, but from the following description it will be manifest that use of my present invention is not limited to any particular mechanism or mechanisms.

The principal objects of this invention are to provide a form of integration table or chart, in which:—

(a) The integrations shall be borne upon a web, band or strip of flexible material, adapted for winding or spooling upon a rotatable member or members;

(b) The integrations shall be arranged, in progressive series or otherwise, both longitudinally and transversely of the web;

(c) The transverse rows of integrations may each have two or more different but related integration characters in each of a plurality of separate longitudinal columns;

(d) The integrations on the web shall be arranged with specific reference to integrations borne by one or more other movable members; and

(e) The longitudinal rows of integrations shall be arranged in progressive groups, transversely of the web.

The means by which the foregoing and other objects are accomplished by my invention, and the manner of their accomplishment, readily will be understood from the following description on reference to the accompanying drawings, in which—

Fig. 1 is a top plan view of a preferred form of my improved web type of integration table.

Fig. 2 is a side elevation showing a typical way of arranging the web for winding upon rotatable members, the larger of said members being partly broken away.

Fig. 3 is a top plan view of a typical form of rotatable members bearing integrations

to which the integrations on the web refer.

Fig. 4 is a top plan view of a typical form of table for identifying the groups of longitudinal columns on the web, and the units of each group.

Having reference to the drawings, the web 5 may be made of paper, cloth, or other suitable flexible material, which preferably should have considerable tensile strength, be so tough as not to be torn or frayed when used in the intended manner, be comparatively inelastic, have a low factor of expansion and contraction under atmospheric and temperature variations, and have a smooth, wear-resisting surface. Said web may be arranged in any desired manner for winding upon, or otherwise being moved by, a rotatable member or members, but in Fig. 2 of the drawings, I have shown it as used in the improved form of calculator referred to in my said co-pending application, in which one end of the web is secured to, and adapted for winding upon a roller 6, while its other

end is similarly arranged with reference to a rotatable cylinder 7. Two cooperating discs 8 and 9 respectively each bearing integrations, furnish data for the selection of the readings to be taken from the integrations on the web 5, provision preferably being made for rotating said discs by rotation of roller 6 or cylinder 7, or vice versa. A stationary table, having ordinates separated into groups which preferably are arranged progressively, as by having dollars, tens, hundreds and thousands groups, a portion only of the dollars group 10, hundreds group 11, and thousands group 12, being shown, is intended to be placed in position to identify the groups and individual columns of integrations on the web 5.

Said web is provided with a series of transverse parallel lines 13, and a series of longitudinal lines 14, the lines of each of said series preferably being arranged symmetrically, so that a plurality of similar rectangular spaces are defined by said lines. In each of a plurality of the transverse rows of such spaces, two or more different but related integrations are inscribed, and means is provided for identifying each thereof, as by placing identifying characters in spaces 15 and 16 which may appear in series not

100

shown, upon the web, or upon some suitable part of the mechanism with which the web is used.

The discs 8 and 9 have their peripheries or 5 other exposed surfaces divided into spaces, as by lines 17 and 18 respectively, in which spaces the integration characters are placed.

As indicated near the top of Fig. 1, more 10 than one series of integrations may be arranged longitudinally of the web, each series preferably starting with a transverse line 19 of zero spaces, and preferably having associated therewith identifying characters appearing in spaces 20 and 21, which may be 15 inscribed in series (not shown) upon the web, may be located at a different part of the calculator from the spaces 15 and 16, or may be combined with said spaces.

As an example of the use of my improved 20 integration table, let it be assumed that it is to be used for calculating interest. The discs 8 and 9 would have their respective peripheries divided into one or more series arranged according to the months of a year, and one 25 or more series of numbers from 1 to 30. The spaces 15 and 16 would have different rates of interest, such for example, as 6 per cent and 8 per cent, noted therein, and in the spaces 20 and 21 other different rates of interest, such as 4% and 5%, would appear. The table of series for dollars, tens, hundreds, and thousands would be placed in position for the divisions thereof to register with the longitudinal columns of spaces on 30 the web. In the transverse rows of spaces shown in the lower part of Fig. 1, there would be placed figures indicating the amounts of interest, at 6% and 8% respectively, on sums starting with one dollar, and 35 increasing from the right-hand side of the web to its left-hand side in conformity with a stationary table such as is shown in Fig. 4. The integrations in each of the longitudinal columns of spaces would show the amounts 40 of interest on the sums, and at the rates, defined in the manner just described, for periods of time starting with one day, and advancing one day for each row of transverse spaces. Starting with the transverse row of 45 zero spaces shown near the top of Fig. 1, integrations would be similarly arranged upon the web, for the rates of interest noted in the spaces 20 and 21, such as 4% and 5%.

The foregoing description of a manner of 50 arranging the integrations for use of the web in computing interest, is given merely as an 55 illustrative example, and is not intended to indicate that my improved integration table is limited to this or any other specific sort 60 of computations, since manifestly the integration characters are susceptible of wide 65 variations to adapt them for various calculations or forms of calculating mechanism, without departing from the intended scope of my invention.

Various modifications of minor details of my improved calculating device will doubtless suggest themselves to those skilled in this art, and I therefore do not desire to limit my invention to the specific matter shown 70 and described herein.

Having now fully described the invention, what is claimed is:—

1. An integration table for use with calculating devices, comprising a web of flexible 75 material adapted to be spooled upon a rotatable member, said web bearing integrations arranged in series both longitudinally and transversely thereof, and referring to a plurality of interdependent movable integrations at one side of said web.

2. An integration table for use with calculating devices, comprising a web of flexible material adapted to be spooled upon a rotatable member, said web bearing integrations 85 arranged in series both longitudinally and transversely thereof, and referring to a plurality of interdependent, circumferential integrations at one side of said web.

3. An integration table for use with calculating devices, comprising a web of flexible 90 material adapted to be spooled upon a rotatable member, said web bearing integrations arranged in series both longitudinally and transversely thereof and referring to a 95 plurality of different but interdependent integration tables at opposite sides of said web.

4. An integration table for use with calculating devices, comprising a web of flexible 100 material adapted to be spooled upon a rotatable member, said web bearing integrations arranged in series both longitudinally and transversely thereof, and referring to a 105 stationary integration table at one side of said web, and to a movable integration table at one side of said web.

5. An integration table for use with calculating devices, comprising a web of flexible material adapted to be spooled upon a rotatable member, said web bearing integrations 110 arranged in series both longitudinally and transversely thereof, and referring to a plurality of independent stationary integration tables at one side of said web and to a 115 movable integration table at one side of said web.

6. An integration table for use with calculating devices, comprising a web of flexible material adapted to be spooled upon a rotatable member, said web bearing integrations 120 arranged in series both longitudinally and transversely thereof, and referring to a plurality of independent stationary integration tables at one side of said web, and to a 125 plurality of independent movable integration tables at one side of said web.

7. An integration table for use with calculating devices, comprising a web of flexible material adapted to be spooled upon a rotatable member, said web bearing integrations 130

tions arranged in a series of pairs spaced both longitudinally and transversely thereof, and referring laterally to a plurality of different integrations not appearing on said web.

8. An integration table for use with calculating devices, comprising a web of flexible material adapted to be spooled upon a ro-

tatable member, said web bearing integrations arranged longitudinally thereof in a plurality of independent series, and referring both laterally and longitudinally to a plurality of different integrations not appearing on said web.

JOHN E. WRIGHT.
